SUPPLYING MECHANISM

Eric A. Holmgren, Lynn, Mass., assignor to United Shoe Machinery Corporation, Paterson, N. J., a corporation of New Jersey

Original application April 13, 1925, Serial No. 22,624. Divided and this application May 7, 1930, Serial No. 450,537

21 Claims. (Cl. 271—62)

This invention relates to mechanism for supplying work-portions to machines which are to operate upon them, it being especially applicable to means for delivering layers of fabric for their combination with other layers to furnish insoles of shoes. The purpose of the invention is to generally improve mechanism of this character, though it is to be understood that its field is by no means limited to the feeding of insole-material.

- 10 The present case is a division of the application for Letters Patent of the United States filed in my name on April 13, 1925, and bearing the Serial No. 22,624, this parent application having, on November 3, 1931, become Patent No. 1,830,604.
- 15 A particular feature of the invention concerns the variation in dimensions of a holder or magazine for work-portions, whereby members which position said portions may be moved to correspond to the size of the insole or other object which is to be made. It further provides for effective presentation in a holder of the work-portions to the means which is to transfer them to the apparatus supplied, and for their certain engagement by the transferring means.
- 20 Another feature of the invention is found in the means by which the work-portions are transferred from their holders to the operating means. Mechanism is provided which is both simple and certain in action.
- 25 The accompanying drawings illustrate one of the several possible embodiments of the invention,
- Fig. 1 being a broken side elevation thereof;
- Fig. 2, a sectional detail taken longitudinally
- 30 through the sheave supporting the counterbalancing weight for the magazine-platform of the mechanism of Fig. 1;
- Fig. 3, a sectional top plan view of the parts illustrated in Fig. 1; and
- 35 Fig. 4 showing the transfer device and immediately adjacent elements of the magazine in broken side elevation.
- 40 There is supported upon a bracket 41 projecting from a frame 26, a skeleton magazine-frame 42. Situated axially of the magazine and fixed in the frame below it is a vertical guide-rod 44, about which moves a sleeve 46 having fixed upon its upper extremity a platform 47 for the support of such work-portions F as fabric layers of composite insoles, these layers being arranged in a stack. The platform, the parts which carry it, and the supported material are counterbalanced by a weight 48, which is hung upon a cord 50 wound about a sheave 52 rotatable upon the bracket 41. The opposite end of the cord is at-
- tached to an arm 49 clamped on the sleeve 46 and sliding upon a vertical rod 51 secured to the frame. Rotatable with the sheave is a ratchet-wheel 54, with which co-operates a spring-actuated detent 56, holding the platform and stack 60 against downward movement. To position the top of the stack at the desired level as the work-pieces are removed therefrom, elevating mechanism is provided, actuated with a mechanism T, which effects the transfer of the blanks from the magazine to operating mechanism. The elevating mechanism includes a pawl 58 engaging the teeth of the wheel 54 and pivoted upon a lever 60 fulcrumed upon the frame and forked to engage a sleeve 62 of the transferring mechanism T, this sleeve being arranged for reciprocation upon the rod 51. Movement of the sleeve occurs each time a piece is transferred from the magazine; and at the same time, through the lever 60, pawl 58 and ratchet 54, the sheave is turned to lift the platform 47 through a predetermined distance. The extent of this feed is somewhat more than the thickness of one of the fabric pieces, so that the transferring instrumentality may always find the element which it is to engage slightly above the 70 level to which the transferring mechanism descends, and therefore in position to receive firm contact. This excess of engaging movement of the transfer mechanism is permitted by frictional connections between the ratchet-wheel and the 75 sheave. The former has a sleeve 64 turning upon a spindle 66 projecting from the bracket 41, the adjacent faces of the sheave and ratchet engaging frictionally. At the opposite end of the sheave is a thrust-bearing 68, against the outer side of 80 which acts a spring-washer 70, this, in turn, abutting against a split nut 72 clamped upon the sleeve. A nut and washer 74 upon the outer extremity of the spindle 66 hold all these co-operating elements against displacement. The force 85 exerted by the washer 70 is sufficient to cause the ratchet and sheave to normally rotate together. When, however, the platform is held against movement by the detent 56 and the transfer mechanism engages the top piece F upon the 90 stack supported upon the platform, the sheave will yield under the pressure, yet offering such resistance as to insure firm contact between the work-portion and the element engaging it. Fixed to turn adjustably below the pawl 58 is a stop-sleeve 75. This has an eccentric or flattened portion, over which the pawl moves without interference. If it is desired to check the upward feed of the fabric without stopping the other elements of the machine, this sleeve may be 105 110

turned until its rounded portion comes opposite the pawl, lifting this from the ratchet-wheel so that, in the reciprocation of the pawl, said ratchet-wheel will not be operated, and the platform will 5 remain at rest. This is of utility in testing and adjusting the apparatus, or upon completing the operation at the end of a period of use. To maintain the effect of the weight 48 in a substantially constant relation to the opposing force 10 exerted by the stack of pieces F, as this varies with the number of pieces upon the platform, a compensating device is associated with the counterbalance. This is furnished by the form of the sheave, which has a spiral, stepped groove 76 for 15 engagement by the turns of the cord 50 wound about it. The steps are of greatest diameter at the ends of the sheave, and least at the center. When the stack is at its maximum height, and therefore heaviest, the extremity of the cord 20 bearing the weight will be at the outer portion of the sheave upon the highest step, while the extremity of the cord connected to the platform will be near the center of said sheave. As the platform rises and the weight falls, the relation will be reversed, the weight-end of the cord descending 25 the incline, and the platform-end rising at the opposite side. In this way, the leverage exerted is gradually oppositely varied, so the effect of the weight is diminished and increased proportionately to the number of work-pieces upon 30 the platform. Therefore, the normal force which the frictional device between the sheave and ratchet is called upon to resist is kept substantially constant.

The work-portions F, which may be of different sizes, corresponding to those of the soles into which they are to enter, are correctly positioned in the magazine by vertical contact-rods extending the entire height of the magazine and arranged in pairs 78, 78 and 80, 80, these pairs being, respectively, at opposite sides and near the extremities of the heel and toe-portions. The rods are carried upon arms 81 pivoted at 82 upon the magazine-frame 42, and are arranged to be moved together by a linkage 84 so proportioned 45 that the shift in the position of one of the rods 78 will similarly move the companion heel-rod, while the toe-rods 80 will have their positions altered correspondingly. The settings of the rods are determined and positively maintained by a finger-lever 86 secured to turn with one of the arms 81 and having a spring-pressed detent 88 engaging any one of a series of notches 90 in a segmental plate 92 mounted upon the lower portion of the magazine-frame. Associated with the 50 notches are sole-size designations, indicating the settings of the rods to give the correct positioning of the work-pieces in the magazine. This movement of the lever 86, by a proper proportioning of the arms and connections, gives a simultaneous 55 adjustment of all the rods for each size of sole which is to be produced, and therefore for the operating mechanism supplied.

To transfer the work-portions one by one from the magazines to the operating mechanism, there 60 is preferably employed pneumatic mechanism T. Upon the sleeve 62 is carried a horizontally extending hollow arm 100, at the outer end of which is a contact-head 102 having in its under side three spaced openings 104. These openings are 65 so related that they will co-operate with the fabric pieces F in the stack over areas extending transversely near the center and in proximity to the opposite ends. Into the arm opens a conduit 106, through which a suction is maintained

by any appropriate means. This conduit is preferably flexible, to permit movement of the arm 100, and includes a swiveled joint 108, which also facilitates this. The suction-head has imparted to it vertical movement into and out of co-operation with the top of the stack in the magazine, to engage and remove the terminal work-piece, and a corresponding movement into proximity to the operating mechanism, to deposit the piece thereon, and then from the operating mechanism preparatory to return to the magazine. It is also oscillated horizontally to effect such transfer from the magazine to the operating mechanism, and the return for the succeeding transfer. To raise and lower the head, the groove in the sleeve 62, which is engaged by the lever 60, also receives the forked end of a bell-crank-lever 110 fulcrumed upon an extension from the bracket 41. The other arm of the lever 110 is joined by a connecting-rod 112 to a lever 114 pivoted for 95 horizontal movement and having a projection 115 entering a cam-groove in a rotatable disk 116. The connections to the lever 114 may extend to different operating mechanisms, to simultaneously 100 actuate the transfer mechanisms T thereat. The disk 116 is fast upon the upper extremity of a shaft 118, which includes an inclined section, and which is geared to some such source of power as a portion of the machine to be supplied. The suction-head is turned about its vertical axis 105 through a gear-segment 124 fixed upon the sleeve 62 and having meshing with it a rack 126, sliding upon the magazine-support and joined by a rod 128 to a bell-crank-lever 130. A projection 131 from the lever 130 enters a cam-groove in 110 the upper face of the disk 116. The relation between the cam and the connecting mechanisms, which respectively raise and lower and turn each suction-head, is such that said head is swung horizontally from the operating mechanism to the magazine; then depressed until it contacts with the top piece of fabric; raised to its former position; again turned until it is over the operating mechanism; lowered to deliver the transferred piece; and raised and returned for 115 another transferring cycle.

For the purpose of temporarily holding the work-portions against the openings 104 of each head 102 for their elevation from the stack, their transfer and final release, the passage of air 120 through the openings is controlled by valve mechanism actuated in the movement of the head. In the conduit 106, at its junction with the head, is a slot in which operates a valve-plate 132 mounted to oscillate upon a pivot 134. Adjacent 125 to the conduit-connection, the head has a relief-opening 136. The plate 132 has two lobes, in one of which is an opening 138, while the other is imperforate. When the opening 138 is aligned with the head 102, the relief-opening 136 is closed by the plate. When said plate is swung in the 130 opposite direction upon its pivot, the imperforate portion moves between the conduit and the opening in the arm to close this, simultaneously freeing the relief-opening. Secured upon the pivot 134 is a small plate 140, slotted at its edge to furnish opposite contact-faces 142, 142, which, in the movement of the plate 132, may strike a pin 144 projecting from the arm 100. The extremes of movement of the valve-plate, as has just been described, are determined by these contacts. A spring 146, extending between an arm 148 fixed to the pivot and the arm 100, acts to hold either of the contact-faces 142 against the pin. 145

Upon the opposite extremities of the plate 140 are contact-projections 150, 152. When the head 102 is over the magazine, the projection 150 is vertically alined with an actuating projection 154 rising near said magazine. Upon the descent of the head for engagement with the upper piece F, the projection 150 strikes the projection 154, swinging the valve-plate 152 into position to open communication between the suction-conduit and head, and to close the relief-opening. This causes the air-current established through the head to hold the work-piece firmly against the openings 104, loss of the suction effected through the opening 136 being avoided by its closure by the valve-plate. This relation continues until the descent of the head over the operating mechanism. Then the projection 152 contacts with an actuating projection 156 rising from the frame. Again the valve-plate is moved, this time to close the suction-conduit and free the relief-opening. This causes the release of the transferred piece from the head 102.

Having described my invention, what I claim as new and desire to secure by Letters Patent of the United States is:

1. The combination with a container for work-portions to be operated upon, said container having a support for work-portions and positioning members co-operating therewith, of means arranged to move said positioning members simultaneously through different distances to correspond to the size of work-portion to be held in the container.

2. The combination with a container having a platform upon which sole-portions may be supported and movable members arranged to contact with opposite sides of the supported sole-portions, of means arranged to move the members simultaneously through different distances at the heel- and toe-portions of the sole to be held in the container and to an extent determined by the size of said sole.

3. The combination with a platform for supporting work-portions, of positioning members arranged in pairs at opposite sides of the work-portions, connections between the pairs of members arranged to cause them to move together, and means for securing the members against movement in different positions.

4. The combination with a platform for supporting work-portions, of positioning members arranged in pairs at opposite sides of the work-portions, connections between the pairs of members, a setting member acting upon the positioning members through the connections, and means for securing the setting member in different predetermined positions corresponding to work-sizes.

5. The combination with a horizontal platform, of positioning rods rising at opposite sides of the platform, levers carrying the rods, connections between the levers, a setting member arranged to move the connections, and an index-plate determining the setting of said member.

6. The combination with transferring means for work-portions movable from a receiving to a delivering position and driving means therefor, of a holder situated at the receiving position and including a support for work-portions, toward which support the transferring means moves, and means actuated by the driving means for moving the support through a predetermined distance to carry the work-portions thereon past the receiving point of the transferring means.

7. The combination with transferring means for work-portions movable from a receiving to a

delivering position, of a holder situated at the receiving position and including a support for work-portions, toward which support the transferring means moves, means for moving the support through a predetermined distance to carry the work-portions thereon past the receiving point of the transferring means, and means arranged to permit the support to yield under the pressure of the transferring means while the moving means remains at rest.

8. The combination with a magazine having a platform for supporting sole-portions, of a transferring device movable horizontally between the operating means and magazine and vertically into receiving position above the magazine-platform and into delivering position, means for elevating the platform to raise the supported sole-portions above the receiving position of the transferring device, and frictional connections between the platform and elevating means.

9. The combination with a platform, of a transferring device movable vertically above the platform into contact with work-pieces supported thereon, means for elevating the platform toward the transferring device, and frictional connections between the elevating means and platform.

10. The combination with transferring means including a movable head provided with a suction-opening, of a magazine having a support for work-portions to be transferred, means for moving the support into position for engagement of the work-portions by the head, and connections between the supporting and moving means permitting said support to yield under the pressure of the head while the moving means remains at rest.

11. The combination with a magazine provided with a movable support for work-portions, of a transferring device movable into engagement with a work-portion upon the support, means for moving the transferring device, means for moving the support in preparation for the engagement of the work-portion by the transferring device, and connections from the moving means for the transferring device to the support-moving means to actuate the latter.

12. The combination with a magazine provided with a platform for supporting work-portions, of a transferring device movable vertically into engagement with work-portions upon the platform, a ratchet-wheel rotatable to elevate the platform, a pawl engaging the ratchet-wheel and being movable to produce the platform-elevating rotation of said ratchet-wheel, and a member carrying the pawl and actuated by engagement with the transferring device.

13. The combination with a magazine provided with a platform for supporting work-portions, of a reciprocating sleeve, a suction-head carried by the sleeve for engagement with work-portions upon the platform, a ratchet-wheel, connections between the ratchet-wheel and the platform, and a pawl oscillated in the reciprocation of the sleeve to rotate the ratchet-wheel.

14. In a magazine, the combination with a movable platform, of a flexible member connected to the platform and carrying a balancing weight, a spindle, a sheave free to turn about the spindle and over which the flexible member operates, an actuating member rotatable about the spindle, and connections to the actuating member for rotating the sheave to elevate the platform.

15. In a magazine, the combination with a movable platform, of a flexible member connected to the platform and carrying a balancing weight,

- a sheave having stepped portions increasing in diameter in opposite directions and over which the flexible member operates, rotating means, and frictional connections between the sheave and 5 rotating means.
16. In a magazine, the combination with a movable platform, of a flexible member connected to the platform and carrying a balancing weight, a sheave over which the flexible member operates, a ratchet-wheel contacting with the sheave, means for forcing the sheave and ratchet-wheel together, a pawl co-operating with the ratchet-wheel, means for oscillating the pawl, and a detent co-operating with the ratchet-wheel. 10
17. In a magazine, the combination with a movable platform, of a flexible member connected to the platform and carrying a balancing weight, a sheave having portions increasing in diameter from the center to its opposite extremities and over which the flexible member operates, and means for rotating the sheave. 15
18. In a magazine, the combination with a movable platform, of a flexible member connected to the platform and carrying a balancing weight, a sheave having stepped portions increasing in diameter outwardly from the center and over which the flexible member operates, a ratchet-wheel rotatable at one extremity of the 20
- sheave, and means for forcing the ratchet-wheel and sheave into frictional engagement. 25
19. The combination with a movable head provided with a suction-opening and a relief-opening, of a suction-conduit connected to the head, a valve-plate pivoted between the head and conduit and movable to simultaneously control the relief-opening and the passage between the head and conduit, a plate secured to the valve-pivot, and fixed contact means located at the extremes of movement of the head and arranged for engagement with the plate to actuate the valve. 30
20. The combination with a movable work-supporting platform, of members for positioning the work upon the platform and between which said platform is movable, a movable carrier for each positioning member, connections between the carriers, and a setting and retaining member joined to the connections and positively holding the positioning members in predetermined positions. 35
21. The combination with a movable platform, of rods between which the platform is movable, a carrier for each rod, connections between the carriers, a setting member joined to the connections, and an index-plate provided with means for retaining the setting member. 40
